Thomas S. Corrane,

ATTORNEY

UNITED STATES PATENT OFFICE.

RICHARD C. DRINKER, OF QUINCY, MASSACHUSETTS.

TRUCK FOR CHARGES IN HEATING-FURNACES.

1,330,245.

Specification of Letters Patent.

Patented Feb. 10, 1920.

Application filed October 3, 1919. Serial No. 328,164.

To all whom it may concern:

Be it known that I, RICHARD C. DRINKER, a citizen of the United States, residing at Quincy, county of Norfolk, and State of Massachusetts, have invented certain new and useful Improvements in Trucks for Charges in Heating-Furnaces, fully described and represented in the following specification and the accompanying drawings, forming a part of the same.

This invention relates to a truck for conveying material into and out of the heating-chamber of a metal heating-furnace, the truck being constructed particularly to travel upon two rows of balls supported in runways transversely to the heating-chamber.

The truck is especially designed to be placed one under each end of a shaft and to support the same so as to permit longitudinal expansion of the shaft when heated.

A truck embodying these improvements is shown in the annexed drawing, in which Figure 1 is a front elevation of a furnace with heating-chamber of much greater width than length and having a series of doors to close its opening, the doors being shown raised to exhibit the trucks supporting the shaft in the heating-chamber. Fig. 2 is a transverse section of the same taken on line 2—2 in Fig. 1; Fig. 3 is an end elevation of the truck carrying an expansion rocker-roll and supported upon two rows of balls; Fig. 4 is a plan of the body of the truck; Fig. 5 is a plan, and Fig. 6 a side view of the rocker-roll used to support the shaft upon the trucks.

The furnace shown forms no part of the invention, but is illustrated merely to show the operation of the truck.

a designates the heating-chamber of the furnace; *b* the doors used to close the front of said chamber, the doors being raised in Fig. 1 and closed in Fig. 2.

45 A combustion-chamber *c* is indicated in dotted lines beneath the floor of the heating-chamber, but the means of heating the chamber is wholly immaterial.

A large shaft *d* is shown supported upon 50 three trucks in the heating-chamber each truck having a rocker-roll *e* mounted thereon, which supports the shaft and is capable of sufficient rotation to permit the longitudinal expansion of the shaft without any 55 obstruction.

The body of the truck has two parallel

side-bars *f* connected by cross-bars *g* with a slot *h* between the cross-bars extended transversely of the side-bars, to receive a counter-balance lug *i* which is projected from the 60 lower side of the rocker-roll.

The balls *k* are shown in Fig. 3 mounted in runways *m* which, like the raceways *j*, are made of somewhat larger radius than the balls to permit lateral play. The cross-bars are made with a flat surface to receive the cylindrical ends of the rocker-roll, which extends over the cross-bars and is parallel with the side-bars.

Each side-bar has its lower side concaved 70 transversely throughout its entire length to form a raceway *j* to rest upon balls *k*, and such side-bars are preferably concaved upon both the upper and lower sides so that the truck may be reversed when the raceways 75 become worn or bent by pressure upon the supporting balls *k*.

The radius of the raceway *j* is made a little greater than the radius of the balls *k*, so as to permit a certain amount of side 80 movement of the truck upon the balls.

The cross-bars have a flat surface on which the ends of the rocker-roll rest with the lug *i* projected down in the slot *h*. The ends of this roll are cylindrical and its upper surface is tapered from the cylindrical ends to the middle line, to form a seat *l* sloped from both ends of the roll toward the middle to center the shaft *d* when laid thereon.

Such sloping is extended around the sides of the roll to the sides of the lug *i*, which has sufficient clearance in the slot *h* to permit a limited rocking of the roll.

Such construction enables the shaft when 95 resting upon such rocker-rolls at both ends, and expanded by heating, to rock the rolls as far as such expansion may require, and to return to an upright position when the load is released.

With a shaft 60 feet in length resting upon the rockers the expansion may be several inches and each end rocker would be turned to compensate one-half of that amount; the sloping surface being formed 105 upon the sides, as well as upon the top of the roll, to keep the shaft centrally supported as the roll is rocked, the balls compensating for lateral alinement.

Three of the trucks with shaft thereon are 110 shown in Fig. 1, two near the ends and one at the middle of the shaft *d*.

Such shafts are sometimes crooked and can be straightened in the heating operation by properly alining the upper surface of the rocker-rolls, so that as the shaft softens in heating its middle and ends may be brought by gravity into a straight line by settling upon the rocker-rolls. This method does not induce strains and obviates annealing after straightening. The 10 runways *m* are in practice extended transversely across the heating-chamber and outside of the same to any desired distance, for loading and unloading the trucks. As such runways are liable to vary slightly in level, provision is made for elevating the rocker-roll upon the central truck when required, so as to bring it level with the other rolls.

Any suitable means may be used to adjust the rocker-roll vertically upon the truck, 20 the simplest means consisting of shim-pieces or plates of suitable thickness shown at *n* in Fig. 3 inserted between the cross-piece *h* and the cylindrical end of the rocker-roll. Such pieces may be provided of various thicknesses so as to be ready for use when required, for compensating large offsets in shaft-rolls when greater diameters are used.

The packings *n* to be inserted between the rocker-roll and the truck-body are inexpensive and durable, and the entire apparatus is therefore very cheap and easily manufactured.

It will be observed that the truck consists of a single casting and is therefore 35 very cheap and possesses no parts liable to derangement.

Having thus set forth the nature of the invention what is claimed herein is:

1. A truck for a metal heating-furnace 40 having raceways to fit upon parallel rows of balls and a slot transverse to the raceways to engage a rocker-roll for the charge.

2. A truck for a metal heating-furnace having raceways to fit upon parallel rows

of balls and a slot transverse to the raceways, 45 a rocker-roll supported longitudinally upon the cross-bars and having a lug fitted movably to the transverse slot to center it upon the truck, and automatically hold the seat for supporting the shaft uppermost. 50

3. A truck constructed according to claim 2, the rocker-roll having a smaller radius at the middle of its length upon the upper side to form a tapering seat to support a shaft or other analogous articles. 55

4. A truck constructed according to claim 2, the rocker-roll having at the middle of its length a smaller radius than at the ends, such reduced radius being carried around the top and sides of the roll and 60 upon the sides of the depending lug for additional strength.

5. A truck for a metal heating-furnace having parallel side-bars with raceways upon the opposite faces of said bars to fit 65 reversibly upon parallel rows of balls.

6. A truck for a metal heating-furnace comprising a casting having parallel side-bars connected by cross-bars, the opposite surfaces of each side-bar being formed with 70 concave raceways to rest upon parallel rows of balls.

7. A truck for a metal heating-furnace having parallel side-bars with raceways to fit upon parallel rows of balls, and cross-bars having a flat upper surface with a transverse slot between such cross-bars, a rocker-roll having cylindrical ends supported respectively upon the flat surfaces of the cross-bars and having a lug fitted movably 80 to the transverse slot to center it upon the truck, and shim-plates fitted between the ends of the rocker-roll and the flat surfaces of the cross-bars for adjusting the height of the roll thereon. 85

In testimony whereof I have hereunto set my hand.

RICHARD C. DRINKER.
